UNITED STATES PATENT OFFICE.

ALBERT C. ELLITHORP, OF CHICAGO, ILLINOIS.

IMPROVEMENT IN OIL-BURNING STEAM-GENERATORS.

Specification forming part of Letters Patent No. 131,088, dated September 3, 1872.

To all whom it may concern:

Be it known that I, ALBERT C. ELLITHORP, of Chicago, in the county of Cook and State of Illinois, have invented a new and valuable Improvement in Steam-Generators; and I do hereby declare that the following is a full, clear, and exact description of the construction and operation of the same, reference being had to the annexed drawing making a part of this specification, and to the letters and figures of reference marked thereon.

Figure 1 of the drawing is a representation of a longitudinal sectional view of my invention. Figs. 2, 3, 4, and 5 are details. Fig. 3 is a longitudinal section. Fig. 4 is a cross-section through *x x*. Fig. 5 is a cross-section through *y y*.

This invention has relation to means for generating steam by heat derived from the combustion of gases or vapors arising from petroleum or other oleaginous substances; and it consists in the construction and novel arrangement of the adjustable flame-passage or combustion-chamber, and in the combination therewith of other devices, all as hereinafter described.

In the accompanying drawing, the letter *A* designates a locomotive to which my furnace and generator have been adapted. *A'* represents the steam-space; *B*, the water-space. *C* represents a fire-cylinder, extending the length of the boiler into the water-back. *D* represents the vertical water pipes or tubes, extending throughout the length of the main fire-flue *C*, and through the water-back. *E* represents the return flues or tubes, through which the non-combustible gases and substances may escape into the smoke-stack. At the front end of the fire-cylinder is the combustion-chamber *B'*, lined with a cylinder, *F*, of fire-brick. *G* represents an inner cone of fire-brick, located within the cylinder *F*, and supported by lugs upon the bottom and sides of said cylinder in such a manner as to leave a circular tapering fire or air throat between its conical surface and the interior cylindrical surface of the lining *F*. This fire-brick cone is arranged to slide upon its lugs within the cylinder *F*, and is, therefore, capable of adjustment to regulate the intensity of the flame-

draft. *H* represents a cylinder of fire-brick, provided with a conoidal point. This fire-brick *H* is located concentrically with the fire-cylinder, leaving a space all around it for the passage of the flame. Suitable lugs are provided at the base and sides of the cylinder *H*, to support it in position. These fire-brick cones, with the cylinder *F*, are designed to give form and direction to the highly-carbonized flame, and to collect and retain the heat therefrom, thus equalizing the same at times of variation in the draft. At the inner end of the cylinder-lining *F* a beveled lip or constriction, *a*, is formed, which is designed to serve as a guide to direct the flames upon the conoidal end of the fire-brick *H*. *I* represents the middle combustion-chamber, where the carbon-gas is mingled with air and superheated steam to create a hydrocarbon flame. *J* represents a funnel-shaped mouth, passing through the breeching, and extending to the cylinder *F*. It is provided with a circular damper, *b*, on the front, so arranged as to regulate the quantity of air to be admitted to the combustion-chamber. *k k* represent the gas-burners, located in the circular space around the cone *G*. Through the axial portion of the cone *G* passes the steam-pipe *f*, which conveys the superheated steam from the pipes located in the water-back. *M* represents the generating-chamber, where the gas is produced from the oil. The gas is conveyed through the pipe *c* to the burners at *k k*. The vertical water-tubes in the front part of the fire-cylinder are protected, when necessary, from the intensity of the flame by means of fire-brick tile. These tubes are usually made tapering from the top toward the bottom, and set by means of a screw-thread at the bottom and expansion rings at the top. This construction facilitates repairs. For the same reason the return-flues should be so arranged that free access to them will be permitted from the top.

What I claim as my invention, and desire to secure by Letters Patent, is—

1. The combination of the fire-cylinder *C* with the fire-brick cones *G* and *H* and the fire-brick lining *F*, substantially as specified.
2. The combination, with the cylinder

C and the fire-brick lining F, of the cones G and H, gas-pipes e, and steam-pipe f, substantially as specified.

3. The air-funnel J, with its damper b, in combination with the fire-cylinder C, the gas-burners k k, and the cone G, substantially as specified.

In testimony that I claim the above I have hereunto subscribed my name in the presence of two witnesses.

ALBERT C. ELLITHORP.

M. H. INSLEY,
D. D. KANE.
